RADIATOR, VALVE, AND TRAP

Eugene W. Goodwin, Bethesda, Md.

Refiled for abandoned application Serial No. 505,428, December 29, 1930. This application March 18, 1938, Serial No. 196,802

2 Claims. (Cl. 257—159)

This application is a re-file of the Eugene W. Goodwin application, Serial No. 505,428, for Radiator, valve and trap, filed December 29, 1930, allowed April 26, 1932, which became abandoned 5 for failure to pay final fee.

My invention relates to radiators for heating purposes and relates particularly to heating radiators adapted to be concealed or enclosed within a recess formed in the wall of a room

10 so as not to extend into the room.

Radiators for steam, hot water or vapor are not attractive in appearance and for this reason and for other reasons it has become a practice to form in the wall of a room, particularly below

15 a window, a recess in which the radiator may be so inserted that it will not project into the room and may be concealed by a screen. Radiators as ordinarily constructed are made up of sections bolted together with an inlet in the section at

20 one end and an outlet in the section at the other end. Radiators have also been constructed with end headers connected by tubes with an inlet in one header and an outlet in the other. In both these constructions it has been the practice

25 to provide the end sections or the headers with valve carrying nipples extending laterally from them for connection with the supply and return pipe. In order to enclose a radiator having these laterally extending nipples within a

30 recess in the wall of a room it has been necessary to restrict the effective length of the radiating surface as to allow for space within the recess for the nipples and valves. This ordinarily means that the length of the effective radiating surface

35 is less by ten to twelve inches than the distance between the sidewalls of the recess. In other instances, to save longitudinal space, the valves and traps are placed beneath the radiator, the vertical space is restricted due to raising the

40 radiator, and the valve is placed in such position as to make its operation inconvenient and awkward.

It is the object of my invention to provide a radiator so constructed that the space wasted in

45 the allowance necessary for the nipples and valves and their operation, adjustment and repair may be utilized, to receive a construction such that the length from end to end and the depth from front to rear of the effective radiating

50 surface shall be coextensive with the width and the length from end to end of the recess. A further object of my invention is to provide a radiator so constructed that means for controlling the inflow and outflow of the heating medium

55 either manually or automatically may be ar-

ranged within the end header or sections, and at the same time the operating handles and devices may be placed in a convenient location.

With the objects above indicated and other objects hereinafter disclosed in view, my invention consists in the construction and combination of elements hereinafter described and claimed. 5

Referring to the drawings:

Figure 1 is a central longitudinal sectional view of a radiator embodying my invention.

Figure 2 is a horizontal sectional view on line 2—2 of Figure 1.

Figure 3 is a horizontal sectional view through the trap end of a modified form of radiator on 15 a line corresponding to line 3—3 of Figure 1.

Figure 4 is a horizontal sectional view similar to Figure 2, but showing a further modification.

In the drawings 1 and 2 indicate the end walls of a recess in the wall of a room under a window 20 or elsewhere in the room, in which the radiator is to be placed so as to conceal or enclose it; that is, so that it will not project into the room.

Radiators as ordinarily constructed have inlet and outlet pipes extending laterally from the 25 headers, end sections or ends of sections, one or both of these pipes being provided with valves. The space taken up by these laterally projecting pipes amounts to four or five inches or more on each end of the radiator and in order to allow 30 for these pipes and the valves carried by them the length of the effective radiating surface of the radiator must be less than the distance between the end walls of the wall recess by the space taken up at each end by the length of the 35 laterally projecting pipes and valves.

In order to make it possible to utilize fully the space of the recess in which a radiator is to be concealed or enclosed I provide a radiator so constructed that the inlet and outlet valves are 40 within the vertical end and side lines of the radiator and as the headers or end sections of the radiator so constructed can fit snugly against the end walls of the recess no allowance need be made for laterally projecting pipes and consequently the entire space between these end walls may be utilized for radiating surface, and this without allowing for any additional width. The valve controlling the inlet is so placed that a device, to automatically actuate it in response to a 45 thermostatic device, may be either attached to it, or incorporated as a part of it and still require no additional concealment space, where automatic control of room temperature is desired.

In the radiator shown 3 indicates a vertical 55

header at the inlet end of the radiator and 4 indicates a vertical header at the outlet end. These headers are connected by a tube or tubes 5 having their ends suitably secured in headers 3 and 4. The outer surfaces of the headers and the connecting tube or tubes are preferably provided with fins 6 to increase their radiating surfaces.

Inlet header 3 is provided at its lower end 10 with an inlet opening 7 provided with a nipple 8 for connection with a supply pipe 9. At its upper end this header is open and is provided with screw cap 10 having a central opening 11. Outlet opening 7 is provided at its upper end 15 within the header with a valve seat 12 to receive valve 13 which is carried by valve stem 14. This valve stem 14 may extend upward through opening 11 in screw cap 10 and be provided at its upper end with a hand wheel 15 or other means 20 for operating it. But in the construction shown the valve stem terminates within the header, being screw threaded at 16 at its upper end to receive screw threaded sleeve 17 which is provided above the screw threaded portion with a shoulder 25 18 to fit against a recess 19 in the inner face of screw cap 10, and extends at reduced diameter upward through opening 11 of the screw cap and is provided above the screw cap with hand wheel 15. A coiled spring 20 between the hand 30 wheel and the screw cap holds the shoulder 18 against recess 19. By rotating hand wheel 15 the distance of valve 13 from valve seat 12 may be regulated to control admission of the heating medium from supply pipe 9.

35 The valve stem 14 is provided with a shoulder 21 on which is secured the lower end of a bellows 23 to the upper end of which is secured a plate 24 which in turn, is held tight against the upper end of header 3 by screw cap 10, the purpose of the 40 bellows being to permit the lower end 22 of the bellows to move with valve 13 toward or away from valve seat 12 while plate 24 at its upper end is so held between the upper end of the header and screw cap 10 as to prevent any leakage from 45 the interior of the header past the valve operating mechanism. While one form of valve of the so-called packless type is shown it should be understood that the invention is not restricted to the particular form or type of valve shown as other valves, either packed, or packless or automatic, 50 may be used.

The wall of header 3 is open towards the radiator tube or tubes 5. Header 4 is closed towards the radiator tube or tubes 5. Header 4 is closed 55 towards the radiator tube or tubes except for a small opening 24 near its lower end to shield the bellows from contact with steam. At its lower end header 4 has an opening 25 from which extends downward nipple 26 for connection with 60 outlet or return pipe 27. At its upper end, within the header, opening 25 is provided with valve 28, preferably removable, adapted to receive the tapered end 29 of valve stem 30. This valve stem 30 extends upward to a disc 31 at the lower end 65 of bellows 32 which carries at its upper end disc 33 from which extends upward, in line with the

valve stem 30 a stem 24, the upper end of which is screwed in screw-threaded plug 35 in the upper end of the header. An air vent 38 is conveniently located within the upper part of the chamber 4' and preferably within the screw cap 5 35. It may be manually operated, as shown in Fig. 1, or of the automatic type. The air within the chamber 4' is expelled through the vent when the heating medium is introduced into the radiator, in order to allow the heating medium 10 to be permitted to enter the chamber above the opening 24. The expansion or contraction of the bellows 32 by change in the temperature within header 4 lifts or depresses the conical end 29 of valve stem 30 toward or from valve seat 28. 15

The headers 3 and 4 are preferably of cast metal and are of such diameter as to provide for receiving within them the inlet and outlet valves and are provided on the sides towards each other with suitable sockets in which the radiator tube or tubes 5 may be secured, and may be constructed to carry one, two or more radiator tubes or series of tubes.

While the construction shown is particularly adapted for use with a so-called two pipe steam, 25 vacuum or vapor system, the substitution for the valve and controlling means (parts 28 and 34) shown, of suitable commercial type of air valve would adapt the radiator for use in a one pipe steam or hot water system.

In the construction shown radiator tube 5 is a flat tube having its vertical dimension much greater than its thickness but instead of this single tube a plurality of tubes cylindrical or of other shape or a series of sections or loops or other form in cross section may be used.

Having thus described my invention what I claim is:

1. A radiator for conveying a heat exchange medium having an inlet header at one end and horizontal radiation tubes in open communication therewith, an outlet header at the opposite end of the radiation tubes provided with an outlet opening, an automatic control valve for varying the size of the said outlet opening located within said header, the said tubes being closed at their outlet ends by said header except for a small opening adjacent the lower side thereof, which is open to the outlet header, a valve associated with the inlet header for controlling the admission of heating medium to the inlet header. 40 45 50

2. A radiator for conveying a heat exchange medium having an inlet header at one end and a plurality of cylindrical horizontal radiation tubes arranged in parallel in open communication therewith, an outlet header at the opposite ends of the radiation tubes provided with an outlet opening, an automatic control valve for varying the size of the said outlet opening located in said header, the said tubes being closed at their outlet ends by said header except for small openings adjacent the lower sides thereof, which are open to the outlet header, a valve associated with the inlet header for controlling the admission of heating medium to the inlet header. 55 60 65
